UNITED STATES PATENT OFFICE.

HERMAN A. LINDSTROM, OF SEATTLE, WASHINGTON.

PUNCH FOR PAPER FASTENERS.

Original application filed November 1, 1921, Serial No. 512,065. Divided and this application filed October 23, 1922. Serial No. 596,259.

To all whom it may concern:

Be it known that I, HERMAN A. LINDSTROM, a citizen of the United States, residing at Seattle, in the county of King and State of Washington, have invented a new and useful Punch for Paper Fasteners, of which the following is a specification.

My invention relates particularly to improvements in machines adapted to perforate paper to receive paper fasteners of the two-pronged variety; and its objects are, to provide a gage whereby a sheet of paper, or a plurality of them, can be so placed or aligned at one corner as to receive uniform perforations for the fastener; to provide a pair of thin, upstanding prongs, cooperating with a plunger, adapted to make a pair of spaced slits or kerfs in the paper, and in diagonal relation with the adjacent corner; to provide simple mechanism to effect said result; and, to provide convenient, integral compartments to carry a special paper fastener, and a sleeve therefor, which is the subject of my application for Letters Patent of the United States, Serial No. 512065, filed November 1, 1921, of which this is a divisional application, and for which this punch is especially adapted.

I attain these objects by the device illustrated in the accompanying drawing, in which—

Figure 1 is a front elevation of the machine complete.

Referring more particularly to the drawing, 1 denotes the base, and 2 a pair of thin, upstanding prongs located in diagonal relation with the base, adapted to make perforations for receiving the prongs of the fastener heretofore mentioned. 3 is a plate, 40 comprising the lower portion of the plunger, provided with a pair of openings 4 for receiving the thrust of the prongs. 5 denotes a gage, consisting of a right angular corner in which to position the adjacent corners of 45 papers to be perforated, or a single sheet as needed. 6 and 7 designate integral compartments to carry a supply of said paper fasteners and a separate sleeve provided therefor.

50 In utilizing the device, preferably the upper left hand corner of the paper to be punched is placed against the gage 5 and above the prongs 2, the right angular proportions of the gage providing a medium

whereby a single sheet, or a plurality of 55 superimposed sheets, can be adjusted or aligned therein so that each will receive uniform perforations. Obviously, a downward thrust of the plunger to the limit permitted by the thickness of the paper will complete 60 the operation. The prongs of the punch, as shown, are sharp pointed, thin, and their body portions of a uniform width, designed to make openings in the paper complementary to said body portions. The paper is 65 then to be removed from the prongs and the fastener applied, the openings in the paper, conforming as they do to the body portions of the prongs of the fastener, hold the fastener securely in place and prevent 70 any side play when the fastener is adjusted for use.

I am aware that a United States Patent, No. 83,640, for paper clip was issued to A. J. Kletzker, on November 3, 1868, wherein 75 a pair of spaced barbed members were adapted to carry and insert in the paper a two-pronged paper fastener simultaneously with the thrust of the plunger and the perforation of the paper. Said device is de- 80 signed to utilize fasteners having prongs of different lengths, but under the construction shown said barbed members are enlarged at their bases and would provide openings in the paper considerably wider than 85 the prongs of the fastener to be used, thus having a tendency to afford lateral displacement of the fastener in the paper.

I am not aware, however, that any one has heretofore produced a punch for paper 90 fasteners especially adapted for making openings in adjacent corner portions of sheets to be fastened, thereby making one two-pronged fastener practically perform the work of two fasteners as ordinarily 95 placed; one which makes spaced slits in the paper which conform in size to the body portions of the prongs of the fastener, and thus prevent lateral play of the fastener when engaging the paper; or, such a punch 100 having a gage by which to position the paper and make uniform corner openings for the paper as heretofore described. In a filing system, where sheets will be added from time to time, said uniform openings as made by 105 this punch will insure that the respective sheets will be placed and maintained in perfect alignment. The mechanism of the pres-

ent machine is exceedingly simple, and the results sought to be obtained are effected by the use of a minimum number of parts.

I claim:

• A punch for paper fasteners, comprising a base, a pair of thin smooth-edged upstanding prongs, spaced apart and in diagonal relation with the base, a plunger operatively connected with the base, having at its lower

terminal a member provided with a pair of 10 openings adapted to receive the thrust of the prongs, and a gage having a right angular recess in which to position and align sheets of paper for receiving pairs of corner perforations in uniform and diagonal relation with adjacent corner portions of said paper. 15

HERMAN A. LINDSTROM.
